CLAIM

The ornamental design for a sharps container as shown and described.

DESCRIPTION

FIG. 1 is a front perspective view of a sharps container showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

(Continued)

The broken lines are included for the purpose of showing portions of the sharps container that form no part of the claimed design.

1 Claim, 7 Drawing Sheets
